UNITED STATES PATENT OFFICE.

JOHN D. TAYLOR, OF BUFFALO, NEW YORK, ASSIGNOR TO THE TAYLOR SIGNAL COMPANY, OF BUFFALO, NEW YORK, A CORPORATION OF NEW YORK.

RAILWAY SWITCHING AND SIGNALING APPARATUS.

SPECIFICATION forming part of Letters Patent No. 752,127, dated February 16, 1904.

Application filed January 12, 1901. Serial No. 42,894. (No model.)

To all whom it may concern:

Be it known that I, JOHN D. TAYLOR, a citizen of the United States, residing at Buffalo, New York, have invented certain new and useful Improvements in Railway Switching and Signaling Apparatus, of which the following is a full, clear, and exact description.

My invention relates to electrically operated and controlled railway switching and signaling apparatus, and more particularly relates to the employment of mechanical, electrodynamic, and electromagnetic appliances for controlling, operating, and safe-guarding such apparatus in its use.

15 The object of my invention is to overcome the defects heretofore existing in such apparatus—namely, the lack of absolute positiveness in action of the mechanical apparatus and the danger of a false indication or release 20 of the mechanical apparatus by a crossing or short-circuiting of the wires of the system, which might otherwise produce such result.

In more specific terms the object of the improvement is to guard against the failure of 25 the locking to hold until properly released (including the event of any accident to the circuit controlling such release) and against failure to release at the proper time.

This invention is furthermore an improvement upon the devices of my former patents 30 No. 516,903, March 20, 1894; No. 554,097, February 4, 1896; No. 605,359, reissued as No. 11,983, May 6, 1902, and No. 707,181, August 19, 1902.

35 This invention consists of improved mechanism for locking when one lever is moved other levers controlling switches or signals whose movements would conflict with the new position of the switch or signal controlled 40 by said one lever moved, automatically-operated mechanism for releasing said locking of other levers, the said magnetically-operated mechanism being actuated by a current produced when the switch or signal controlled 45 by said one lever has made its complete movement, and a new arrangement of circuits and magnets for securing a more certain release of the locking and to prevent such release or

false indication in the event of accident to the circuit controlling the same.

The accompanying drawings, in which like characters of reference indicate like parts, show in Figure 1 a side elevation of my invention sufficiently in section to show the working parts; Fig. 2, an enlarged view in perspective of a portion of the same; Fig. 3, a section on the line xx of Fig. 1; Fig. 4, a section on the line yy of Fig. 1; Fig. 5, a detail plan view of the detent, pawl, wiper, and adjacent mechanism. Fig. 6 is a diagram of the circuits.

Referring to Figs. 1 to 5, inclusive, the bar 1, which is provided with a suitable handle, has a slot 2 formed therein. This slot has its middle portion parallel to the direction of movement of the bar, and the two end parts are inclined thereto in the same direction and at equal angles. A roller 3 is pivoted to the jaw 4, formed on the end of the tappet-bar 5. The locking between levers is effected by means of these tappet-bars and bars transverse thereto in the usual manner employed in mechanical and other interlocking mechanisms which are well known. The bar 1 is guided by guide-plate castings, one of which is shown at 6, and by straps 7 across the top of these guide-plates and is supported at the bottom by a slab 8, which lies in a vertical position and occupies a part of the space between the guide-plates 6. The slab 8 at the left in the drawings is of a thickness to substantially fill the space between the guide-plates 6, while at the right its thickness is reduced, so as to form a rectangular space or slot between said slab and an adjacent plate 6 to form a recess within which the detent 9, pawl 10, and the wiper 11 are free to move upon their respective pivots. In this recess and pivoted to the slab 8 are the latch or detent 9, the pawl 10, and the wiper 11. The detent 9 has an upwardly-projecting lug 12 at one end, which enters a notch in the lower edge of the bar 1, the said notch forming the shoulders 13 and 14. The detent 9 is supported in a position to hold this lug 12 in the notch in the bar 1 by the pawl 10, engaging in a notch 15

in the detent 9. The detent 9 in this position, the bar 1 is capable of moving only to such an extent as to carry the roller 3, attached to the tappet-bar 5, along the horizontal portion of the slot 2, but not to cause the roller to enter the inclined portions of the slot 2.

- Directly under the pawl 10 a magnet 16 is supported, having an armature 17, guided by pins 18, attached to the cores of the magnets. 10 A rod 19 is attached to the armature 17 in such manner that when the armature is attracted by the magnets 16 this rod 19 bears against a horizontal arm 20 of the pawl 10, so as to push it out of engagement in the 15 notch 15 of the detent 9. The detent 9 is then free to fall by gravity, which carries the lug 12 out of the path of the shoulders 13 and 14 in the bar 1, thus permitting the bar 1 to make a further movement, which carries the 20 roller 3, attached indirectly to the tappet-bar 5, through one of the inclined portions of the slot 2.

The pins 18 extend downwardly through the armature 17 and support the magnets 21, 25 which are axially in line with the magnets 16. Non-magnetic washers 22 are interposed between the cores of the magnets 21 and the armature 17. The armature 17 normally rests down upon the washers 22 in proximity 30 to the cores of the magnets 21 and is drawn from that position only when the magnets 16 are energized, and should the magnets 16 be energized by a crossing or short-circuiting, as hereinafter described, the current passing in 35 series, in such event both 16 and 21 would be energized and the armature 17 by reason of its position would be prevented from rising to give a false indication or release, as herein-after more fully described in connection with 40 the circuits.

An upwardly-projecting lug 23, having beveled shoulders, is formed on the opposite edge of the detent 9. The notches 24 and 25 are formed on the lower edge of the bar 1 in such 45 position that when the shoulders 13 or 14 are bearing against the lug 12 these notches 25 or 24 are directly over the lug 23, which permits the detent 9 to drop. The detent 9 is replaced in the notch between 13 and 14 by the uncut 50 portion of the bar 1 between the notches 24 and 25 passing over the lug 23, thus depressing this end of the detent 9 and elevating the opposite end. During the time that this portion of the bar 1 lying between the notches 55 24 and 25 is passing over the lug 23 the lug or shoulder 13 on the bar 1 engages a fork of the wiper 11, causing it to partially rotate on its pivot and causing an arm of the wiper 11 to replace the pawl 10 in engagement with the 60 detent 9. The purpose of the wiper is to insure the pawl 10 in engaging with the detent 9 and to insure that the armature 17 is pushed away from the magnets 16 by the downward action of the arm 20 of the pawl 10 on the 65 end 19.

A vertical slot is cut through the slab 8 directly over the rod 19, and a rectangular tongue 26 slides loosely in this slot and is of such length that when the rod 19 is at its lowest point the said tongue 26 drops by gravity 70 below the under side of the bar 1, and when forced upwardly by the thrust of the rod 19, due to the raising of the armature 17, said tongue projects into the path of travel of the bar 1. To permit of this, a longitudinal slot 75 is cut in the lower rear edge of the bar 1, as shown in broken outline in Fig. 2. A lug 27 is rigidly secured on the bar 1, projecting downwardly and occupying part of the space between the shoulders 13 and 14 in the notch of 80 the bar 1, the lug 27 being in the same vertical plane as the tongue 26, but not with the detent 9, and projecting into said longitudinal slot in the bar 1, so as to come in contact with the tongue 26 when the said tongue is 85 raised by the rod 19. When the magnets 16 are energized, the tongue 26 is pushed upwardly, so as to lie within the path of travel of the lug 27, the object being to prevent the movement of the bar 1 during the time that 90 the magnets 16 are energized in the direction opposite to the initial movement as otherwise a false indication might be obtained.

In Figs. 1 to 5, inclusive, the parts are shown in full line in the position they would occupy 95 at the close of the middle movement or just before the final movement to reverse position. The full reversed position of the bar 1, roller 3, contacts *a* and *b*, detent 9, and pawl 10 is shown in Fig. 1 in broken outline, and the contacts 100 *a* and *b* would stand insulated at the extreme left. In the reversed position the bar would be at the extreme right, the roller 3 at its lowest point, the contacts *a* and *b* at the extreme right, while the wiper 11, the detent 9, and the pawl 10 would be in the position indicated in broken 105 outline and the lug 27 would be at the right of the tongue 26; but since in moving from the normal the plates *a* and *b* in closing with *d* *g* and *f* *h*, respectively, cannot make a circuit they produce no effect until they close with the contacts *c* *d* and *e* *f*, respectively, at the close of the middle movement of the bar 1. In like manner the plates *a* and *b* produce 110 no effect in passing from reverse to normal until they close with the contacts *d* *g* and *f* *h*, 115 as will appear hereinafter.

To explain further. Suppose the operator should pull the bar 1 toward its reversed position until stopped by the detent 9. This 120 would establish a circuit including the battery and a switch-operating motor, as hereinafter fully described, and would cause the "reversal" of the track-switch. As soon as the track-switch is completely "reversed" a current generated by the motor, as hereinafter described, would circulate in the coils of magnet 16. This is for the purpose of releasing the bar 1 to make its final movement to the 125 reversed position; but as this current is of 130

sensible duration, if the operator should push the bar 1 back toward its normal position during its continuance, even though the wiper 11, acting through the pawl 10, does force 5 the armature away from the magnet, it would be drawn back again as soon as the wiper passed the pawl, and the detent 9 would be released, thus permitting a full movement of the bar 1 to the "normal" position, while the track- 10 switch controlled by it would be in the reversed position. The tongue 26 effectually prevents this, because it prevents the bar 1 being moved back again during the continuance of the current.

15 The bar 1 is connected by means of a rod 28 with contact-springs *a* and *b*, which are electrically insulated from each other, which springs make electrical connection between the contact-blocks *c d*, *d g*, and *e f*, *f h*, as 20 hereinafter fully described.

The diagram of Fig. 6 shows the application of the apparatus and system to a switch leading from the main track 29 to a side track 30 and the signals governing the two routes 25 which may be set up. All parts of the mechanism, including the circuits and circuit-controllers, are shown in this figure in what is technically known as the "normal" position, which in this case would mean that the switch is 30 set for the main track and the signals indicate "danger." In this normal position the lug 12 of the detent 9 will be down and out of engagement with the bar 1. The full part of the bar 1 to the left of the shoulder 14 will 35 be over the lug 12. The notch 24 will be over the lug 23 of the detent 9, and the wiper 11 will be in the position shown in broken lines in Fig. 1, and the latch 10 will be in the position shown in broken lines in that figure. 40 In the extreme reverse position the lug 12 of the detent 9 will be down and out of engagement with the bar 1. The full part of the bar 1 to the right of the shoulder 13 will be over the lug 12. The notch 25 will be over 45 the lug 23. The latch 10 will be in the position shown in broken lines, and the wiper 11 in the position shown in full lines in Fig. 1.

To reverse the switch—that is, set it for the side track—the bar 1 is placed in the position 50 shown in Fig. 1 in full lines. This places the contact-springs *a* and *b* so that *a* makes electrical connection between the contact-blocks *c* and *d* and *b* makes electrical connection between the contact-blocks *e* and *f*. This closes 55 a circuit of the battery 31, so that the current flows through the wire 32, magnets 21, wires 33 34, contact *c*, spring *b*, contact *f*, wire 35, contact-arm *i*, wire 36, armature of switch-operating motor 37, wire 38, contact-arm *j*, coils 60 of motor field-magnet 39, wires 40 41, back to the battery 31. This causes the rotation of the armature 37, which acting through intermediate mechanism connecting it with the switch-rail moves the switch-rail. When the 65 switch-rail is completely home and locked,

the pole-changing switch, consisting of the arms *i* and *j* and suitable contacts, is reversed by means of the mechanism, as described in my Patent No. 681,589, August 27, 1901. The reversal of this pole-changing switch establishes a circuit including the switch-operating motor 37 and the indication-magnets 16, so that the current produced by the continued rotation of the motor-armature, due to momentum, flows from the armature 37, wire 7 36, contact-arm *i*, wire 42, motor-field magnet-coils 39, wires 40 41 43, indication-magnet 16, wires 44 45, contact *c*, spring *a*, contact *d*, wire 46, contact-arm *j*, wire 38, back to the armature 37. This current energizes 8 the magnets 16, causing them to lift the armature 17 and the rod 19, which acting on the pawl 10 disengages it from the detent 9, allowing the detent to drop out of engagement with the bar 1. This permits the bar 1 to be 8 moved into its complete reversed position, (shown in dotted lines in Fig. 1,) thus releasing the lever controlling the signal, giving trains the right to enter the side track 30.

To reverse or clear the signal, a bar similar 9 in its essential features to the bar 1 and connected with the contact-spring *k*, Fig. 6, is moved so that the spring *k* makes electrical connection between the contact-blocks *l* and *m*. This closes the circuit of the battery 31, 9 so that the current flows through wires 47 48, contact *l*, spring *k*, contact *m*, wire 49, contacts *n* and *o*, connected by the arm 50, wire 51, magnet 52, wires 53 54, field-coils 55, armature 56 of the signal-operating motor, 10 wires 57 58, contact *p*, contact-springs *q*, contact *r*, wires 59, 60, and 41, back to battery 31. This causes the rotation of the signal-motor armature, which acting through the intermediate gearing comprising the clutch operated by the magnet 52 puts one of the signal-arms—say the lower one (indicated at 61)—into the clear or safety position, and when the signal-arm has 11 fully reached the safety position the springs *q* are thrown out of contact with the contact *p*, thus breaking the circuit just described between *p* and *q*, as fully described in my former patent, No. 707,182, August 19, 1902. The magnets 52 and 69 are the selector-magnets 11 fully described in my Patent No. 707,180, August 19, 1902. The construction is such that when the switch 50 is in one position the magnet 69 will be energized and cause the clutch to engage the mechanism setting the signal—say signal 70—and when the switch 50 is in 12 the other position the magnet 52 will be energized and in like manner cause the other signal—say 61—to be set; but this break in the circuit is shunted by the magnet 62 and wires 71 and 72, which when the electrical connections between *p* and *r* are broken becomes energized and operates the brake or clutch which holds the signal in the clear position, substantially as shown and described in my said former patent, No. 516,903, March 20, 1894.

The contact-arm 50 is connected mechanically to the switch-rail and moves with it in such manner that when the switch is "normal" the arm 50 bridges the contacts *s* and *t* 5 and when the switch is reversed the arm 50 bridges the contacts *n* and *o*.

To put the signal in a normal position, a bar corresponding to bar 1, which is connected to the spring *k*, is pushed back again until 10 stopped by a detent corresponding to the detent 9. This movement is sufficient to carry the spring *k* away from the contact *l* and put it into electrical connection with *m* and *u*. The separation of *l* and *m* electrically stops 15 the current through the magnet 62, thus releasing the signal 61, so that it returns to the normal position by the action of the counter-weight and at the same time returns the springs *q* to contact with *p* and *r*, and the electrical 20 connection of *m* and *u* establishes a circuit containing the signal-operating motor and the indication or releasing magnet 63, so that the current generated by the rotation of the signal-motor armature, due to the descent of the 25 counterweight, flows from the armature 56 through wires 57 58, contact *p*, springs *q*, contact *r*, wires 59 60 41 34 65, through the magnet 63, wire 66, contact *u*, spring *z*, contact *m*, wire 49, contact *n*, contact-arm 50, contact 30 *o*, wire 51, magnet 52, wires 53 54, field-coils 55, back to armature 56. This energizes the magnet 63, causing it to release the operating-bar corresponding to the bar 1 of the switch-operating lever, thus permitting the lever-bar 35 corresponding to bar 1 to make the final part of its movement, which movement releases the locking between the bar of this signal-operating device and the switch-operating bar 1, which permits the switch to be put back 40 to normal. The final movement also breaks the electrical connection between the contacts *m* and *u*, leaving the line or controlling wire 49 normally cut off from other parts of the interlocking machine.

In putting the signal-lever into the normal position (the first above described) a release from the detent (shown in the switch-operating mechanism at 9) is not effected and none is required, since in setting up any route the 45 signal is the last function to be cleared and there is no other locking to be released by the final movement of the signal-lever; besides, it is necessary to maintain the electrical connections between the contacts *l* and *m* in order 50 to maintain the current through the magnet 62 and hold the signal to "safety." In some particular cases it is required to clear a distant signal after a home signal is cleared. In this case the locking between them is effected by 55 means of a circuit-closer controlled by the home signal—such, for instance, as that formed by the springs *q*—making connection between the contacts *v* and *r*, which connects the return-wire from the distant signal to the common return-wire. 60

To put the rail-switch in its normal position, the bar 1 is pushed in until stopped by the detent 9. This movement lowers the tap-pet-bar 5 into its middle position, locking in this case both the signal-levers, and places the contact-springs *a* and *b* so that they may make connection between the contact-blocks *d* *g* and *f* *k*, respectively. This closes the circuit of the battery 31, so that the current flows from battery 31 through wire 32, magnets 21, wires 75 33 67, contact *g*, spring 2, contact *d*, wire 46, contact-arm *j*, wire 38, armature 37, wire 36, contact-arm *i*, wire 42, field-magnet coils 39, wires 40 and 41, back to battery 31. This rotates the armature 37, which through the intermediate mechanism disclosed in my former patent, No. 681,589, August 27, 1901, replaces the rail-switch in its normal position. When the rail-switch is completely home and locked, the pole-changing electric switch, comprising 80 the contact-arms *i* and *j*, is changed, cutting off the battery-current from the motor and establishing a circuit comprising the switch-operating motor 37 and indication-magnet 16, so that the current generated by the continued 85 rotation of the armature flows from the armature 37 through wire 38, contact-arm *j*, field-magnet coils 39, wires 40 41 43, magnet 16, wires 44 68, contact *h*, spring *b*, contact *f*, wire 35, contact-arm *i*, wire 36, back to the armature 37. This energizes the magnet 16 and releases the bar 1, as before described, to make its final movement. The final movement of the bar 1 in this case releases the lever controlling the signal governing the main track-route. This signal may now be reversed; but it is unnecessary to describe this operation, as it is exactly like the operation before described. 90

The magnets 21 are suspended under the 105 magnets 16 by means of the brass rods 18, which serve as guides for the armature 17. The armature 17 rests normally on the poles of the magnets 21, with thin brass washers 22 interposed to prevent the actual contact of the magnetic metals comprising the armature 17 and the cores of the magnets 21. The object of the use of these magnets 21 is to prevent the armature 17 being lifted by the magnets 16 in case an accidental cross between the 110 wires 35 and 46 causes a current from the battery 31 to flow through the coils of the magnets 16, as such a current must go in series through the magnets 21 and 16, and as the armature is closer to the magnets 21 than to the magnets 16 it is prevented from being lifted by the magnets 16, which might otherwise give a premature release of the bar 1. The currents operating the switch also go 115 through these magnets; but as these currents are cut off before the currents generated by the switch-operating motor-armature are sent through the magnet 16 there is no resistance offered to the movement of the armature under the influence of the magnets 16 when prop- 120 125 130

erly energized by said indication-current. This magnet 21 is not needed in connection with the signal-indication magnet 63, as a cross between the signal-control wires would 5 not affect the magnet 63.

In Fig. 6 I have shown a second spring and set of contact-blocks $w\ x\ y\ z$ and a selector-magnet 69, by which another signal—say the upper one shown at 70—is operated; but as the 10 operation would be identical with that of the one described further description is unnecessary.

Having thus described my invention and its method of operation, what I claim is—

- 15 1. The combination of an interlocking mechanism of a bar actuating the same, a detent for holding said bar against final movement, a wiper actuated by said bar for locking said detent, a motor, an operating-circuit, an indication-circuit, and means for shifting the motor from the operating to the indication circuit, and a magnet included in said indication-circuit for unlocking said detent, substantially as and for the purposes set forth.
- 20 2. The combination of an interlocking mechanism of a bar actuating the same, a detent for holding said bar against final movement, a lug on said detent capable of engagement with said bar to move said detent, a latch for locking said 30 detent, a wiper actuated by said bar for rendering positive the engagement of said latch in lock with said detent, and electrically-operated means for unlocking said mechanism which locks said detent capable of acting upon said latch, substantially as and for the purposes set forth.
- 35 3. In combination with an interlocking mechanism, a bar for actuating the same, a detent for holding said bar against final movement, means for throwing said detent in position for engagement by the initial movement of the bar, a latch, a wiper actuated by said bar for rendering positive the engagement of said latch in lock with said detent by the further movement of said bar, and electrically-operated means for unlocking said detent to permit final movement at the proper time, comprising a magnet, an armature, and a rod on said armature capable of engaging said latch, 40 substantially as and for the purposes set forth.
- 45 4. The combination with an interlocking mechanism of a bar actuating the same, a detent for holding the bar against final movement, mechanical means for locking said detent in engagement with said bar, consisting of a pawl and a wiper which is actuated by said bar and which forces said pawl into engagement with said detent, and means for releasing said detent comprising a magnet, an 50 armature, and a rod on said armature capable of actuating said pawl, substantially as and for the purposes set forth.
- 55 5. The combination with a mechanical interlocker of a bar actuating the same, a detent for holding said bar against final movement, 6 a pawl, and a wiper actuated by said bar for forcing said pawl to lock said detent, and a magnet and armature for forcing said pawl out of lock with said detent, substantially as and for the purposes set forth.
- 60 6. In combination with a mechanical interlocker, a bar actuating the same, a detent for holding said bar against final movement, a pawl, and a wiper for forcing said pawl into lock with said detent, a magnet, armature and 75 rod for forcing said pawl out of lock with said detent, a tongue actuated by said magnet engaging said first-mentioned bar and holding the same against reversed movement after said detent is unlocked and until said magnet is de-energized, substantially as and for the purposes set forth.
- 70 7. In combination with a mechanical interlocker, a bar actuating the same, a detent for holding said bar against final movement, a 80 pawl, a wiper for forcing said pawl into lock with said detent, a magnet, armature and rod for forcing said pawl out of lock with said detent, said wiper having jaws engaging said bar whereby it is actuated and an arm which 85 throws said pawl into engagement, and at the same time forces said armature out of contact with said magnet, substantially as and for the purposes set forth.
- 75 8. In combination with a mechanical interlocker, a bar for actuating the same, a detent thrown into engagement with said bar by the movement of said bar, a pawl locking said detent and actuated by a further movement of said bar, electrically-actuated mechanism for 90 releasing said pawl, and means for holding said bar against a reverse movement until the electrically-actuated mechanism has ceased to be energized, substantially as and for the purposes set forth.
- 90 9. In combination with a mechanical interlocker, a bar actuating the same, a detent for holding said bar against final movement, mechanical means for locking said detent, a magnet, an armature and rod for unlocking said 100 detent, and a second magnet in series with said first magnet acting upon said armature in the event of improper energizing of said first-mentioned magnet to prevent the movement of said armature, substantially as and for the purposes set forth.
- 105 10. In a railway switching and signaling system, in combination with a battery and a mechanical interlocker, a bar actuating said mechanical interlocker, a detent for holding said bar against final movement, a lug on said 110 detent, and a projection on said bar for engagement with said lug to replace said detent, an electric switch, a motor, mechanism for actuating said switch, a circuit including 115 said motor and said battery, a pole-changing electric switch, a magnet for unlocking said detent, a circuit including said motor and said

nagnet for energizing said magnet to cause the unlocking of said detent, substantially as and for the purposes set forth.

11. In a railway switching and signaling system, in combination with a battery and a mechanical interlocker, of a bar actuating said mechanical interlocker, a detent for holding said bar against final movement, an electric switch, a motor, mechanism for actuating said switch, a circuit including said motor and said battery, a pole-changing electric switch, a magnet for unlocking said detent, a circuit including said motor and said magnet for energizing said magnet to cause the unlocking of said detent, and a tongue actuated by said magnet and a notch in said bar to receive said tongue and hold said bar against a reverse movement while said magnet is energized, substantially as and for the purposes set forth.

12. In a railway switching and signaling apparatus, a mechanical interlocker governing the action of the switch-lever and the signal lever, an electric switch, a switch-bar actuating said mechanical interlocker and said switch, and a track-switch-operating circuit and switch-operating motor; an electric switch, a signal-bar actuating said interlocking mechanism and said electric switch, a signal-operating circuit and a signal-operating motor, detents for holding said bars against final movement and mechanical means for locking said detents, magnets for unlocking said detents and circuits capable of being closed to include said magnets with their respective motors and acting as generators to energize said magnets, substantially as and for the purposes set forth.

13. In a railway switching and signaling apparatus, in combination with a mechanical interlocker, an electric switch, a circuit including a battery, a track-switch-operating motor and motor mechanism for actuating said track-switch, a bar actuating said mechanical interlocker and said electric switch, a detent governing said bar, means for locking said detent operated by the movement of said bar, and mechanism for unlocking said detent consisting of a circuit, a pole-changing switch and a magnet, said circuit including said magnet and said track-switch-operating motor, said magnet being energized to unlock said detent by said motor acting as a generator after the pole-changing switch is thrown, substantially as and for the purposes set forth.

14. A railway switching and signaling apparatus consisting of a mechanical interlocker, a battery, a track-switch-operating motor, a circuit including said battery and said motor,

an electric switch for closing said circuit, a bar actuating said mechanical interlocker and 60 said electric switch, a detent for holding said bar against final movement, means for locking said detent, electrically-operated means for unlocking said detent consisting of an indication-circuit, a magnet, a pole-changing 65 switch for closing said magnet in said indication-circuit with said motor; and a signal mechanism comprising a signal, a signal-operating motor, a circuit including said signal-operating motor and said battery, a switch for 70 closing the same, a bar for actuating said switch and said interlocker, a detent for holding said bar against final movement, mechanical means for locking said detent, and electrically-operated means for unlocking said detent 75 consisting of a magnet, a switch and said signal-operating motor and indication-circuit including the same, substantially as and for the purposes set forth.

15. A railway switching and signaling apparatus, consisting of a mechanical interlocker, a battery, a track-switch-operating motor, a circuit including said battery and said motor, an electric switch for closing said circuit, a bar actuating said interlocker and said electric switch, a detent for holding said bar against final movement, means for locking said detent, electrically-operated means for unlocking said detent consisting of an indication-circuit, a magnet, a pole-changing switch 90 for closing said magnet in said indication-circuit with said motor; and a plurality of signals and signal-operating circuits, each including the signal-operating motor, a switch, a shunt-circuit and a magnet for holding the signal at safety, and having separate circuits including said motor, said switch, said magnet and said battery, and a corresponding plurality of selector-magnets for throwing their respective signals, and indication-circuits and 100 magnets energized by said signal-motor, a plurality of bars actuating said interlocking mechanism and the switch belonging to its respective circuit, detents for holding said bars against final movement, mechanical means for locking said detents, and means for unlocking said detents when their respective magnets are energized substantially as and for the purposes set forth.

In witness whereof I have hereunto set my 110 hand in the presence of two witnesses.

JOHN D. TAYLOR.

Witnesses:

M. E. SNYDER,
E. C. RISCHMAN.
